2 SHEETS—SHEET 2.

UNITED STATES PATENT OFFICE.

WALTER B. SMITH, OF NEW HAVEN, CONNECTICUT.

TOY CONSTRUCTION MEMBER.

1,212,700.

Specification of Letters Patent. Patented Jan. 16, 1917.

Application filed April 20, 1916. Serial No. 92,474.

To all whom it may concern:

Be it known that I, WALTER B. SMITH, a citizen of the United States, residing at New Haven, in the county of New Haven 5 and State of Connecticut, have invented a new and useful Improvement in Toy Construction Members; and I do hereby declare the following, when taken in connection with the accompanying drawings and the 10 characters of reference marked thereon, to be a full, clear, and exact description of the same, and which said drawings constitute part of this application, and represent, in—

Figure 1 a perspective view of a girder-member constructed in accordance with my 15 invention. Fig. 2 a perspective view of a partially assembled girder comprising four girder-members and a male and a female end or coupling-member. Fig. 3 a similar 20 detached view of one of the female coupling-members. Fig. 4 a similar view of one of the male coupling-members. Fig. 5 a similar broken view showing two girders in 25 process of being coupled together end to end. Fig. 6 a similar broken view showing two girders in process of being coupled at a right angle to each other. Fig. 7 a broken 30 view showing six girders coupled together so as to radiate at right angles from each other.

My invention relates to an improvement 35 in toy construction-members of the class in which a variety of effects in structural-steel work may be simulated, the object being to produce toy construction-members designed 40 with particular reference to ease and variety of assemblance without the use of screws, nuts and bolts, or similar fastening means.

With these ends in view, my invention 45 consists in toy construction-members of the structural-steel type, having certain details 50 of construction as will be hereinafter described and pointed out in the claims.

In carrying out my invention, I employ a 55 plurality of girder-members 2 perforated as at 3 and 4 for the simulation of structural-steel girder work, provided along their side edges with assembling-flanges 5 and formed at each end with an assembling finger 6 standing at a right angle to the plane of 60 the member and each formed with an inwardly struck coupling-nub 7. Each member 2 is also provided near its ends with transversely arranged coupling-slots 8 arranged in line with the said fingers 6 which 65 are intersected by the central longitudinal axis of the girder-member 2.

Four girder-members 2, such as described, are assembled to form a hollow rectangular girder by means of a pair of U-shaped end coupling-members 9 and 10 of which the former is characterized as a female member by having a slot 11 located at one side of the center of its outer face 12, and the latter as a male member by having a yielding tongue 13 formed in its outer face 14. The female member 9 is provided at the corners of its outer face 12 with four outwardly struck conical nubs 15, while the male member 10 is provided in the corners of its outer face with corresponding conical depressions 16. Each of the said coupling-members has two parallel, inwardly extending wings or arms 17 each of which is formed near its outer edge with a transverse coupling-slot 18. The outer faces 12 and 14 of the said coupling-members 9 and 10 are struck inward to form clearance recesses 19 located directly opposite each other on the open sides of the said members, each of these recesses terminating at its inner end in an assembling-slot 20 and each recess having an inwardly struck, conical depression 21. The recesses 19 and slots 20 aforesaid are formed for the reception of the assembling fingers 6 of the girder-members 2 as shown in Fig. 2, 85 while the depressions 21 are formed for the reception of the nubs 7 on the assembling fingers 6 of the said girder-members, for retaining the fingers 6 in the slots 20.

When the tongue 13 of one of the male 90 end coupling-members 10 is inserted into the slot 11 of one of the female end coupling-members 9, the nubs 15 of the female-member snap, so to speak, into the corresponding depressions 16 of the male-member 95 in coupling the girder end to end to assist in preventing the axial rotation of the girders with respect to each other. The girders produced by combining four girder-members 2 and a pair of end coupling-members 9 and 10, may be combined with each other in an endless variety of ways three of which are indicated in Figs. 5, 6 and 7 respectively. In Fig. 5, two girders are shown 100 as being combined end to end by the insertion of the tongue 13 of one girder into the slot 11 of the other girder. In Fig. 6, two girders are shown as being combined at a right angle by inserting the tongue 13 of one girder through one of the side slots 8 of 110 another girder. The structure of Fig. 7 is produced by combining the modes of cou-

pling illustrated in Figs. 5 and 6. Another range of structures may be built by inserting the tongues 13 of the male coupling-members into the triangular openings 3 of the girder-members, the range of variation being practically endless, and constituting the interest of the "game."

Particular attention is called to the fact that all of these variations are produced 10 without the employment of screws, bolts and nuts, or other fastening means—all replaced in my construction by end coupling-members having tongues and slots for receiving the same.

15 The invention herein described might obviously be embodied in girders having other than rectangular form, the only requirement being that their end coupling-members shall be provided with yielding tongues and slots 20 for the reception thereof.

I claim:—

1. As a new article of manufacture, toy-construction members comprising girder-

members and end-coupling members, the said girder-members being provided at their 25 respective ends with inwardly projecting assembling-fingers, and the said coupling-members being formed with slots for the reception of the said assembling-fingers, and means for holding the said fingers in place 30 in the said slots after their introduction thereinto.

2. As a new article of manufacture, toy-construction members comprising girder-members and male and female end-coupling 35 members, the said girder-members being furnished at their respective ends with inwardly projecting assembling-fingers, and with coupling-slots located adjacent thereto, and the said male and female end-coupling 20 members being formed with slots for the reception of the said assembling-fingers, and respectively formed also with coupling-tongues and coupling-slots.

WALTER B. SMITH.
